US0D1034591S

(12) **United States Design Patent** (10) **Patent No.:** **US D1,034,591 S**
(45) **Date of Patent:** **** Jul. 9, 2024**

(54) **INPUT DEVICE FOR ELECTRONIC AND COMPUTER EQUIPMENT**

(71) Applicant: **Endor AG**, Landshut (DE)

(72) Inventor: **Bernhard Conrad**, Buch am Erlbach (DE)

(73) Assignee: **Endor AG**, Landshut (DE)

(**) Term: **15 Years**

(21) Appl. No.: **35/512,731**

(22) Filed: **Aug. 30, 2021**

(80) **Hague Agreement Data**

Int. Filing Date: **Aug. 30, 2021**

Int. Reg. No.: **DM/216721**

Int. Reg. Date: **Aug. 30, 2021**

Int. Reg. Pub. Date: **Oct. 15, 2021**

(57) **CLAIM**

The ornamental design for an input device for electronic and computer equipment, as shown and described.

DESCRIPTION

The patent or application file contains at least one drawing executed in color. Copies of this patent or patent application publication with color drawing(s) will be provided by the Office upon request and payment of the necessary fee.

1. Input device for electronic and computer equipment

1.1 : Bottom

1.2 : Top

1.3 : Left

1.4 : Right

1.5 : Perspective

1.6 : Front

1.7 : Back

The areas in the reproductions shown in the color yellow form no part of the claimed design.

1 Claim, 7 Drawing Sheets

(7 of 7 Drawing Sheet(s) Filed in Color)
